UNITED STATES PATENT OFFICE

GUSTAVE HEIN, OF ASTORIA, NEW YORK, ASSIGNOR, BY MESNE ASSIGNMENTS, TO
LEVITON MANUFACTURING COMPANY, A CORPORATION OF NEW YORK

CONNECTER PLUG

Application filed September 3, 1927. Serial No. 217,483.

This invention relates to improvements in connector plugs; especially connector plugs for electric smoothing irons and other well known utensils.

5 An object of the invention is to provide a connector plug having the usual parts for attachment to an electrical conductor and to engage the contacts of the iron or other utensil; and comprising in addition a simple 10 switch for controlling the electric current.

A further object of the invention is to provide a connector plug containing a switch consisting of very few parts, easy to manipulate, and costing comparatively little to produce.

An important advantage afforded by this invention is that the smoothing iron or the like can be attached to the ordinary conductor joined by the ordinary connector plug to the usual outlet of the electrical supply circuit of a house or building, without requiring the complete separation of the conductor from the outlet of the supply circuit when the use of the iron is to be temporarily discontinued. By merely opening the switch, the iron can be set aside for the time being, but remains perfectly handy for further services whenever the housewife or other operator again needs it.

30 Other objects and advantages are set forth in the following description, taken with the drawing, which discloses a form of my invention. The description however is illustrative only and I may vary the shape, size 35 and arrangement of parts without exceeding the scope and meaning of the terms of the appended claims.

On the drawing—

40 Fig. 1 is a top plan of one half of the plug according to my invention showing the switch therein;

Fig. 2 is a longitudinal section of same on the line 2—2 of Fig. 1; and

45 Figs. 3, 4 and 5 are detail views of some of the parts of the switch.

The same numerals identify the same parts throughout.

The plug as shown herein comprises a casing of insulation, consisting of a top 1 and a bottom 2, secured together in any suitable 50 fashion. At one end is an opening 3 into which is inserted the cord containing the two insulated current conductors joined to the outlet of the supply circuit; and at the other end are open recesses 4 and 5 in which are 55 fixed contacts in the form of the usual split clamps which receive and grip the contact prongs of the smoothing iron or the like when the plug is attached. One of these clamps is indicated at 6 in Figure 2, the other being 60 omitted from the drawing. At 7 is a partition extending lengthwise through the plug and on one side of the partition is a passage 8 leading from the opening 3 to the recess 4, so that one supply conductor can be affixed 65 directly to the clamp in this recess. The clamp 6 in the other recess 5 is united to the remaining conductor by way of a switch in a compartment 9, on the opposite side of the partition 7. It will be seen from Figure 1 70 that the partition 7 thus divides the interior of casing into two conductor channels, one a channel 30 comprising the recess 4 and passage 8, and the other a channel 31, comprising the recess 5, switch compartment 9 formed 75 by an offset portion of the partition 7 and the passage from this compartment to the opening 3. It will also be seen that these two conductor channels are insulated from one another by the partition 7 for substantially the 80 entire length of the plug.

This switch is mounted on a journal or bearing post 10 made fast to the casing in the compartment 9, and on the journal is pivoted 85 a switch arm 11, in the form of a bell crank lever, having at one end a lateral projection 12, and at the other an aperture 13. At 14 is a contact piece, having a lateral projection 15, in position to be engaged by the projection 12 on the arm 11, and this piece is connected 90

to the clip 6 in the recess 5 by some rivet 16 or the like which holds this clip in the casing. Contact 14 and clip 6 are secured by the rivet 16 to the top of a ledge 33 in the channel 31 and the contact 14 is bent downwardly into the channel 31 and thence extends along the outer wall of the channel. In closing the switch the contact 12 moves into abutting engagement with the fixed contact 14 which is held in position and prevented from swinging around the rivet 14 by outer wall of the channel 31. A member 17 engages one end of the journal 10 and carries a binding screw or post 18 for the other supply wire which passes into the compartment 9. Hence, when the switch is closed, the post 18 is in circuit with this clamp 6. The outer end of member 17 is held against swinging movement about the post 10 by the partition 7 and wall of the plug casing.

The arm 11 is operated by a member 19 of insulation, also pivoted on the journal 10. This actuator 19 projects to the outside of the plug through recesses in the meeting edges of the parts 1 and 2, providing a slot 20. It also has an opening 13 at its inner end, and is joined to the arm 11 by a resilient element 21. This element is in the form of a looped U-shaped spring, having legs 22, the ends of which are bent to enter the apertures 13 of the arm 11 and actuator 19. This spring 21 is a "floating spring"; that is, it moves bodily when the actuator is manipulated into different positions to throw the arm 11 in opposite directions, as one may wish to open the switch or close it. The legs 22 tend normally to spread apart, and when the switch is closed, as indicated in full lines on Figure 2, the spring 21 holds the actuator 19 firmly against one end of the slot 20 and the arm 11 against the projection 15. When the switch is opened, the spring holds the actuator 19 against the other end of the slot 20, and the arm 11 against a corner 23 of the partition 7, as indicated in Figure 2 by broken lines; and the ends of the slot 20, the projection 15 and corner 23 thus serve as stops for the arm 11 and actuator 19. Washers 24 lie between the actuator and the parts 11 and 17 and a nut 25 on the journal 10 bears on the upper washer.

Figure 1 shows the switch closed. To open it the actuator is manipulated to broken line position, pulling the spring over to the right. Thus the legs 22 are forced towards each other, and they approach a position more in line with the length of the plug. When the spring at last is carried over to the right of a line joining the centers of the journal and the aperture 13 in the arm 11, it exerts a force on the arm 11 which becomes effective to turn the arm 11 in a counter-clockwise direction. The switch then quickly opens. Movement of the member 19 in the other direction again will quickly close it.

As previously stated one of the terminal

wires of the cord extends through the passage 8 and is connected to the clip in the recess 4 and the other terminal wire of the cord is connected to the member 17. It will be seen that the two terminal wires after entering the opening 19 bend outwardly in opposite directions and each then bends around a part of partition 7. This disposition of the wires in the channels relieves the wire binding means on clip in recess 4 and on the member 17 from undue strain which might pull the wires loose from the binding means.

The plug thus comprises only a few parts, can be easily operated, made at low cost, and is not liable to get out of order.

Having described my invention, what I believe to be new and desire to protect and secure by Letters Patent of the United States is:—

1. A connector plug comprising a casing open at one end for the reception of a conductor cord, a partition in said casing forming two conductor channels extending from said opening to the opposite end of said plug, one of said channels being formed intermediate its ends with an enlarged portion forming a switch compartment, conducting clamps in said channels at said opposite end, a switch in said compartment comprising a movable contact, and a fixed contact connected to the inner end of one of the clamps.

2. A connector plug comprising a casing formed with a conductor channel extending therethrough, a conductor clamp in said channel near one end thereof, a switch in said channel, comprising a fixed contact having a contacting portion extending along a side wall of said channel, and a second contact movable toward said wall to engage said stationary contact and means engaging said clamp and stationary contact for holding said clamp and stationary contact in position.

3. In a device of the class described, a casing having a conductor channel extending therethrough, a switch located in said channel and comprising a contact secured to the bottom of said channel, and bent parallel with the side wall of said channel and a second contact movable toward said wall to engage said first named contact to close a circuit and holding means for a terminal conductor connected to said first named contact.

4. A connector comprising a casing having a partition extending therethrough and forming separate conductor channels, a switch located in one of said channels and comprising a stationary bearing post, a contact pivotally mounted on said post, a fixed contact adapted for engagement with said movable contact, a conducting member mounted on said post and terminal binding means carried by said member, said member being held between said partition and the wall of said casing.

5. A connector comprising a casing having a partition extending therethrough, and

forming separate conductor channels, a switch located in one of said channels and comprising a stationary bearing post, a contact pivotally mounted on said post and means 5 for conducting current to said contact comprising a member loosely mounted on said post and held against swinging movement by said partition and the wall of said casing, and terminal binding means carried by said member.

6. A connector plug comprising a casing forming a conductor channel, a conductor clamp in said channel adjacent one end thereof and a switch in said casing comprising a 15 fixed contact secured to the inner end of said clamp and having a flat contacting portion lying against a side wall of said channel and a movable switch contact adapted for abutting engagement with said fixed contact.

20 7. A connector plug comprising a casing having a conductor channel extending therethrough, a conductor clamp in said channel adjacent one end thereof, said channel being formed with a ledge on which the inner end 25 of said clamp is secured, a switch in said channel comprising a fixed contact secured on said ledge and electrically connected with said clamp, said contact being bent downwardly from said ledge into said channel and 30 extending along said wall and a second contact movable toward said wall to engage said fixed contact.

8. In a device of the class described, a casing having a switch compartment therein, a switch actuator pivotally mounted in said compartment and projecting outside said casing, a pivoted switch arm in said compartment, a fixed contact adapted to be engaged by said arm, a resilient operating connection 35 between said actuator and arm mounted to act from different positions to move said arm quickly into and out of engagement with said contact.

9. A connector plug comprising a casing 40 having a switch compartment therein, a stationary bearing post in said compartment, a switch actuator pivotally mounted on said post, a fixed contact, a contact pivotally mounted on said post and acting from different 45 positions of said actuator to cause said pivoted contact to engage and disengage said fixed contact.

10. A connector plug having a compartment therein, an actuator pivotally mounted 50 in said compartment and projecting to the outside of said plug, a switch comprising a pivoted switch arm in said compartment, members for joining a conductor to said arm, one of which members is a fixed switch contact, the plug providing stops for the arm and actuator and a U-shaped spring connected at its end to the actuator and switch arm and movable with the actuator.

11. A connector plug comprising a casing 55 having a compartment therein, a bearing post

in said compartment, a switch arm pivoted on said post, a member on said post and carrying terminal binding means, an actuator also pivoted on said post, the casing having a slot through which the actuator projects and 70 a looped spring having its ends engaging the arm and the actuator, the ends of the slot providing stops for the actuator and the plug having parts, one of which is a fixed contact to serve as stops for the arm.

75 In testimony whereof I affix my signature.
GUSTAVE HEIN.
